CONTROL MECHANISM FOR BELT DRIVEN APPARATUS

Raymond C. Straube, Three Rivers, Mich., assignor to Fairbanks, Morse & Co., Chicago, Ill., a corporation of Illinois

Application October 28, 1932, Serial No. 639,989

6 Claims. (Cl. 105—107)

This invention relates to improvements in control mechanism for belt driven apparatus, and more particularly to means for adjusting the tension of the driving belts of sliding base engines, such as are commonly used in connection with railway motor cars.

An object of the present invention is to provide an improved belt-tensioning means for railway motor cars, embodying a lever, for shifting the motor relative to the car, which is operatively connected to the motor, through cushioning means disposed between the motor and the actuating elements, so as to impart a gradual belt-tensioning movement of the motor, when the lever is operated, the cushioning means serving, during the time the engine and belt are operating under load, to protect the belt from casual tensioning shocks.

A further object is to provide an improved control mechanism for belt-driven motor cars, which includes a lever for shifting the motor relative to the car frame, improved means for latching the shift lever in adjusted position, and improved means for preventing effects of vibration and twisting stresses of the shift lever and associated parts.

A still further object is to provide an improved control mechanism for tensioning the drive belt of a railway motor car, which is simple and inexpensive to construct and maintain, and is composed of a minimum number of parts which are readily and easily removed and replaced in case of wear or breakage.

Still further objects will appear from the following detailed description of parts, and from the accompanying drawings, in which:

Fig. 1 is a longitudinal sectional elevation of a preferred form of railway motor car, to which the present improvements are applied in preferred form; Fig. 2 is an enlarged fragmentary longitudinal elevation of a preferred form of control mechanism; Fig. 3 is a section along line 3—3 in Fig. 2; Fig. 4 is an enlarged fragmentary plan view, partially in section, of a portion of the mechanism shown in Fig. 2, certain parts being removed for clearness, and Fig. 5 is a sectional elevation taken along line 5—5 in Fig. 2.

Referring by reference numerals to the drawings, the numeral 10 designates, generally, a preferred form of railway motor car, which includes a suitable frame structure 11 mounted upon car axles 12, to which are secured wheels 13 which may be of conventional type. An internal combustion engine 14, of a type usually employed

on railway motor cars, is provided with a crank shaft 15, to which is secured a driving pulley 16 for transmitting power to a driven pulley 17, by means of suitable belting 18, the pulley 17 being secured to an axle of the car.

As will be noted in the drawings, the engine 14 is disposed for sliding movement, longitudinally of the car, for effecting adjustment of the tension of the driving belt 18, the engine being, by preference, mounted upon suitable guide members 19 secured to the frame structure of the car. The sliding movement of the engine is obtained by a novel manually operated mechanism which includes, by preference, a manual control lever 20 pivotally secured to a car sill member 21, as by a pin 22. The pin extends through a bearing block 23 which is secured to the sill, as by bolts 24, extending through the sill member. The pin 22 pivotally carries on its inner end a member 25 which is secured in spaced relation to the lever arm 20, as by a bolt 26 and a sleeve 27. The member 25 and lever 20 thus provide a pivotal frame which straddles the sill member to insure a smooth pivotal lever movement, confined, however, to its intended plane of actuation. A pin 28 is, by preference, secured between the member 25 and lever 20, and is arranged to engage selectively, a plurality of notches 29 formed in an eye member 30 in the nature of a slide, which is disposed to extend between the legs of the lever frame, and so prevents any appreciable lateral or angular displacement of the slide member, for a purpose hereinafter appearing. This slide member is, by preference, provided with an eye or apertured portion 31 through which extends a rod member 32, the bore 31, by preference, being of a size to permit free endwise movement of the slide upon the rod. The rod 32 is pivotally secured, as by a pin 33, to a bracket portion 34 formed on the engine 14. Surrounding the rod 32, is a cushion spring 35, which bears, at one end, against a shouldered or abutment portion 36 formed on or carried by the rod, and on the other end against the end portion of the slide member, which, in turn, is urged by the pressure of the spring toward a stop and adjusting nut 37 which may be locked in adjusted position by means of a lock nut 38, each nut being threaded secured to the portion of the rod which extends through and beyond the slide member.

In Fig. 1 the parts of the mechanism are shown in idling position, such that the slack in the belt 18 is sufficient to prevent the belt gripping the pulley to an extent to transmit power to the rear 55

axle of the car. When the car is to be operated, the shift lever 20 is moved toward the dotted position shown in the drawings, such movement causing the slide member 30 to compress the spring 35, which results in gradual sliding movement of the engine on the guideways as imparted through compression of the spring, the extent of sliding movement, for a predetermined movement of the lever, being limited by engagement 10 of the slide member with the stop nut 37. As will have been noted, such control movement tends to increase the distance between the centers of the pulleys 16 and 17, and thus tensions the belts 18 to transmit power for driving the car.

15 The shift lever 20 is arranged to be latched in adjusted positions, by means of a manually controlled detent device, which includes a rocker arm 39 pivotally connected to the lever 20 by means of a pin 40, one arm of the rocker being connected by means of a link 41 to a pivoted pawl structure 42. This structure, by preference, consists of a pair of pawl members 43 which tend to engage, respectively, a pair of ratchet members 44, which are removably secured, at opposite 20 sides of the lever, to a supporting structure 45 securely attached to the frame structure of the car, as by bolting. A spring 46 is, by preference, connected to the lever 20 and to an arm portion of the rocker arm 39, so as to urge the pawl members 25 into engagement with the teeth of the ratchet. It will be noted that the pressure of the spring 46 serves to bias the lever 20 clockwise (Fig. 2), so as to cause the pawl members to bear against the ratchet teeth in lever-latching position. It will be seen that by manual manipulation 30 of the rocker arm 39, the pawls 43 may be withdrawn and the shift lever operated in any desired direction. It has been found that the provision of double ratchet and pawl members 35 eliminates any tendency for the lever to twist or vibrate during operation of the car.

When applying a new belt, or after considerable service, certain adjustments are needed to insure proper tensioning of the belt when the shift lever 45 is operated. Usually an adequate adjustment may be effected by means of the notches 29 provided on the slide, by moving the rod about the pin 33, until the pin 28 is disengaged from one 50 notch, the engine then being moved to a position to permit the pin 28 to engage another notch, the notched portions of the slide member being biased into latching relation with the pin by means of a coil spring 41 mounted on the pin 33. This spring is anchored to the engine, at one 55 end, and looped over the top of the rod at its other end, and so tends to move the plunger clockwise or downwardly, (Fig. 2). This spring also serves to prevent transmission of vibrations from the engine to the rod, side and lever.

60 A further, somewhat closer adjustment may be obtained by varying the initial position of the slide 30, through the adjusting nut 31, which, as will have been observed, also varies the effective range of movement of the slide, along the rod 32.

65 By the adjusting feature above noted it will be seen that instantaneous facilities are afforded to compensate for belt stretch or different lengths of belts, as well as to care for different size pulleys. It will also be noted that the slide member 30 serves a dual purpose, in that it transmits the control movement of the shift lever 20 to the spring 35 for shifting the engine during operation, and also provides a rough adjustment for taking up belt slack as the belt is subjected to 70 stretch in use. The control device herein de-

scribed is simple in operation and is composed of a minimum number of parts consistent with the results obtained.

It will, of course, be understood that the present detailed description of parts and the accompanying drawings relate to only a single preferred executional embodiment of the invention, and that substantial changes may be made in the described arrangement and construction of parts without departing from the spirit and full intended scope of the invention.

I claim:

1. In combination with a railway motor car and engine, a sliding base for said engine, a guide arm pivotally secured to said engine, a member slidably carried by said arm, and provided with a series of notches, a lever provided with a pin adapted to be seated selectively in said notches, for actuation of the notched member, an abutment on said arm, adjacent its pivoted connection to said engine, and a spring, disposed about said arm, between the abutment and a portion of said notched member, for transmitting a movement of the lever, to effect sliding movement of the engine.

2. In a railway motor car of the class described, means for slidably shifting an engine along its base, including a lever having an opening therethrough, an eye member extending through the lever, and having a plurality of notches selectively engageable therewith, a rod pivoted at one end to the engine, and extending through the eye member, and a spring carried by the pivot end of the rod, and slidably movable along the rod by means of said eye member for cushioning actuation of said engine.

3. In an engine shifting mechanism for a railway motor car, a shifting lever consisting of a handled frame, a ratchet and a pawl therefor on each side of said lever, a slide extended through said frame and adjustably connected thereto, a guide rod by which said slide is carried, an abutment on said rod, a spring between the slide and abutment, said rod being pivotally secured to the engine, and a stop near one end of the rod for adjustably limiting the range of movement of said slide, with respect to said rod, the lever, slide and stop coacting for positively shifting the engine in one direction, and the lever, slide, spring and abutment coacting in shifting the engine in the opposite direction.

4. An engine shifting mechanism for use in a railway motor car, including a lever consisting of a handled frame, an eye member projecting through said frame, a cross piece carried by said frame, the eye member having a row of notches adapted selectively to engage the said cross piece, a rod extended through an eye of said eye member so as to permit sliding movement of the eye member therealong, a pivotal connection of said rod to said engine, an abutment on said rod adjacent its pivotal connection, a compression spring carried by said rod between said abutment and said eye member, and a spring associated with the pivotal connection of said rod, and tending to displace said rod in a direction to keep said eye member in notched connection with the cross piece of said frame.

5. In combination with a railway car frame and engine of the class described, a sliding base for said engine, an actuating lever having a bifurcate portion pivotally secured to said frame, an apertured actuated member extending between the furcate portions, and adjustably associated with said actuating lever, a rod extending

slidably through apertures of said actuated member so as to serve as a guide therefor, and pivotally secured to a portion of said engine, a shoulder on said rod close to its engine connection, and a resilient element forming a cushioning connection between, said shoulder and actuated member.

5 6. In combination with a railway car frame and engine, a sliding base for said engine, an actuating lever pivotally secured to a portion of the car frame, a rod pivotally secured to a portion of said engine, a lever-actuated member slidably

disposed on said rod, and provided with a plurality of slots, a pin on said actuating lever for selectively engaging the slots in said actuated member, a spring in biasing relation to said rod, and tending to urge said pin into the slot selected therefor, an abutment on said rod adjacent its pivotal connection with the engine, a shoulder on said actuated member, and a spring concentric with said rod, and disposed between said abutment and said shoulder, and constituting a cushioning connection therebetween.
